CLAIM

The ornamental design for handgun magazine spring as shown and described.

DESCRIPTION

FIG. 1 is a perspective view of the handgun magazine spring showing my new design;

FIG. 2 is a left side view thereof;

FIG. 3 is a back view thereof;

FIG. 4 is a top view thereof; and,

FIG. 5 is a bottom view thereof.

The translucent gray overlay on the bottom end of the handgun magazine spring is provided to represent an unclaimed portion of the handgun magazine spring that is disclaimed. The translucent gray overlay itself forms no part of the claimed design.
